PROCESS OF TREATING HYDROCARBON OIL

Filed Sept. 19, 1933

UNITED STATES PATENT OFFICE

2,099,920

PROCESS OF TREATING HYDROCARBON OIL

Harold V. Atwell, White Plains, N. Y., assignor to Gasoline Products Company, Inc., Newark, N. J., a corporation of Delaware

Application September 19, 1933, Serial No. 690,055

7 Claims. (Cl. 196—10)

This invention relates to processes for the production of light products, such as gasoline, from relatively heavy hydrocarbon oils.

- It is an object of my invention to provide a process whereby relatively heavy hydrocarbon oils may be converted into relatively high anti-knock motor fuel at high efficiency with minimized gas and other losses. More specifically it is an object of my invention to provide a process for cracking relatively heavy hydrocarbon oils to cause conversion thereof into lighter products and to reconvert gas formed to liquid products falling within the desired boiling range, so that they may be blended in the final desired product.
- 15 In accordance with my invention fresh charging stock, such for example, as gas oil, is cracked under relatively high temperature and moderately low pressure to produce a large percentage of gasoline per passage through the cracking zone without regard to the amount of incondensable gases produced at the same time. This step of the process is directed mainly to the making, by drastic vapor phase cracking, of large amounts of relatively high anti-knock value motor fuel in a single passage through a cracking zone. This conversion may be as high as 30 to 40% of products in the gasoline boiling range, per pass, or even higher. The resulting cracked products are separated into liquid residue, cycle stock, i. e. 30 distillate stock of higher boiling point than that of the final desired product, liquid distillate of the desired end point, and incondensable gases. The liquid residue is withdrawn from the process or treated in any conventional manner, the cycle stock is preferably returned, wholly or in part, to the cracking zone for further conversion, the liquid distillate is preferably subjected to stabilization to remove undesirable light gaseous products therefrom, and these products may be 35 combined with the incondensable gases mentioned, while the stabilized distillate is conducted to a blending zone or withdrawn from the process. The mixture of incondensable gases, high in unsaturates, particularly olefines, is then subjected to a polymerizing action adapted to cause conversion thereof into liquid products falling in the boiling range desired for the final product to be produced, e. g. gasoline, and the polymerized products are separated into liquid residue, cycle stock, distillate of the desired end point and incondensable gas. The liquid residue may be withdrawn from the process or treated in any conventional manner, while the cycle stock is preferably returned wholly or in part, to the main 50 cracking zone for further conversion. The dis-
- tillate is preferably subjected to stabilization to remove therefrom undesirably light incondensable gases, and these gases may be combined with the incondensable gases mentioned as separated from the polymerized products, and the mixture is subjected to pyrolysis under conditions adapted to produce liquid products falling in the desired boiling range. The resulting pyrolyzed products are separated into heavy tar, cycle stock, distillate of the end point desired for the final 10 product and incondensable gas. The distillate may be conducted to the blending zone first mentioned and blended with the distillate produced by the cracking operation and that produced by the polymerizing operation, or may be withdrawn from the system separately. Any two or more of the distillates produced may be blended as desired. The tar may be withdrawn from the system in the usual manner, or subjected to any conventional treatment, while the cycle stock is 20 preferably returned wholly or in part, to the original cracking zone for further conversion of light products. This cycle stock is mainly aromatic and a portion thereof may advantageously be combined with the incondensable gases resulting from the cracking operation prior to the polymerization thereof, so that reaction between the cycle stock and the gases undergoing polymerization will take place with attendant production of larger amounts of light products in the desired 25 boiling range than would follow from the treatment of either the cycle stock or the gases alone. The gas separated from the pyrolyzed products, which contains substantial quantities of unsaturates such as olefins and the like, may also be 30 combined with the gases undergoing polymerization so that conversion thereof into the final desired product results.
- In operating according to the preceding description it is desirable to fractionate the cracked vapors to take overhead a distillate of relatively low end point, such for example, as 250 to 300° F. This distillate need not necessarily be sharply fractionated. Incondensable gases resulting from the cracking operation are preferably converted to liquid by the polymerizing process mentioned, but other processes may be used, if desired, to accomplish this result. For example, the gases may be subjected to high temperature pyrolysis, or they may be caused to react with heavier oils such as pressure tar, tar distillate, or reflux condensate, with or without the aid of a catalyst. The liquids thus produced are preferably fractionated to yield a heavy naphtha of high anti-knock value suitable for blending with the light 55

naphtha from the primary operation to make specification motor fuel.

The above mentioned and further objects and advantages of my invention, and the manner of attaining them will be made clear in the following description taken in conjunction with the accompanying drawing.

In the drawing reference numeral 1 indicates a charging line through which fresh charging 10 stock, such as gas oil, for example M. C. gas oil of 35° A. P. I. gravity or any other suitable clean hydrocarbon oil adapted for relatively drastic cracking without deleterious formation of coke, is introduced into cracking heater or furnace 2 under pressure generated by pump 3. The heater 2 is preferably of the tubular type and is adapted to raise the temperature of the oil passing therethrough to a relatively high value of, for example, 900° to 1100° F., preferably 950° to 1000° F. thereabout, under a moderately low pressure, e. g. in the range of atmospheric to 450 pounds per square inch or more, but preferably about 200 pounds per sq. inch. During its passage through the cracking heater the oil undergoes relatively 25 drastic cracking, sufficient for example, to cause conversion of 30-40 per cent thereof to products in the gasoline boiling range, per passage. The highly heated cracked products pass from the cracking heater through transfer line 4, having 30 control valve 5, into evaporator 6, wherein preferably substantially the same pressure is maintained as at the outlet of the cracking heater, e. g. 200 pounds per square inch, but wherein a lower pressure may be used if desired. In the 35 evaporator cracked products separate into vapors and a liquid residue. The residue is drawn off from time to time or continuously through draw-off line 7, and may be diverted from the system or treated in any well known manner, while the 40 vapors pass overhead through vapor line 8 into fractionator tower 9. In the fractionator undesirably heavy fractions of the vapors are condensed as reflux condensate, and all or part of this condensate may be recycled to the cracking heater 2, through lines 10 and 11, any remainder being diverted from the process through line 12. Reference numeral 13 indicates a refluxing line 45 through which cooling fluid may be supplied inside the top of fractionator 9 in the usual manner, thereby regulating the boiling characteristics of the vapors remaining uncondensed at the top of the tower. Vapors remaining uncondensed at the top of the fractionator tower are withdrawn through vapor line 13' and condenser 14, the resulting condensate being introduced into receiver or gas separating drum, 15. In this drum the 50 incondensable gases separate from the condensate and these gases, which are relatively dry on account of the pressure imposed thereon, may pass off through vent line 16 and line 17 to storage, but preferably pass through line 18, and compressor 19 into polymerizing heater 20, in which they are subjected to polymerization under a temperature of, for example, 800° to 1000° F. preferably 55 about 900° F., and under a high pressure, which may be in excess of 1000 lbs., for example, in the neighborhood of 2000 pounds per square inch, more or less. In this heater the olefinic portion of the gases undergo polymerization to liquids, some of which fall within the boiling range of the 60 final desired product. The polymerized products pass off from the heater 20 through line 21, having reducing valve 22, into evaporator 24, wherein separation thereof into liquid residue and vapors takes place. As the polymerized products leave

the heater they are quickly cooled by the intermixture therewith of quenching oil introduced through line 25, this quenching oil being either 5 fresh charging stock for the system or any other suitable cool product. Liquid residue is drawn off from the evaporator 24, either continuously or from time to time, through line 26, and may be conducted to storage or treated in any well known manner. The vapors pass overhead through vapor line 27, into fractionator tower 28, wherein 10 condensation of undesirably heavy fractions takes place. Part or all of the reflux condensate formed in the fractionator may be diverted from the process through lines 29 and 30, but preferably a substantial part or all of this reflux condensate is recycled through line 31 under pressure generated by pump 32, to the cracking heater 2, for further conversion. Reference numeral 15 33 indicates a line through which a cooling liquid may be supplied to the inside of the fractionator tower in the usual manner, to control the boiling characteristics of the vapors remaining uncondensed at the top of the tower. The uncondensed vapors pass off from the top of tower 28 through vapor line 34, and condenser 35, the resulting condensate being collected in receiver or 20 gas separator 36. In this receiver incondensable gases separate from the condensed liquids and these gases may pass off from the separator through vent line 37 and line 38 to storage, but 25 preferably pass through line 39 into pyrolyzing heater or furnace 40 under pressure generated by compressor 41.

In the heater 40, which is preferably of the tubular type, the gases are subjected to pyrolysis 35 by being raised to a relatively high temperature under low pressure and held at this high temperature for a relatively short period of time. The temperature to which the gas is heated may be between about 1400° and 1800° F., preferably in 40 the neighborhood of 1600° F., more or less, and the pressure may range from substantially atmospheric or less to as high as a hundred pounds, however relatively low pressures are ordinarily preferable, and the time of contact may vary 45 from about one-tenth second to about five seconds, more or less. In this coil the gases, which are more or less paraffinic in nature, are preferably largely reduced to liquid products, some of which fall within the boiling range of the final desired 50 product. The effective pressure on the gases to be heated in furnace 40 may be reduced to a subatmospheric value by mixing a diluent, such as steam or CO₂, with the gases entering the furnace, valved pipe 41' being provided for this purpose. 55 The products of pyrolysis pass from the heater 40, through line 42, into evaporator 43, being cooled upon leaving the heater by the mixture therewith of a quenching oil introduced through line 44. This oil may be fresh charging stock or 60 any other suitable material. In the evaporator 43 vapors separate from liquid residue and the latter is drawn off from time to time or continuously through pipe 45, either for diversion from the process, or for any further treatment of a conventional nature. The vapors pass over-head 65 through vapor line 46 into fractionator 47 and therein undergo partial condensation, the heavier constituents, having a boiling point higher than that desired for the final product, being separated 70 out as reflux condensate. The uncondensed vapors pass off from the top of the fractionator through vapor line 48 and condenser 49, the resulting condensate being collected in gas separator or receiver 50. In this receiver incondensa- 75

ble gases separate from the liquid condensate and these gases may be diverted from the process through pipe 51, but preferably are wholly or in part combined with the gases introduced into polymerizing heater 20, combination being brought about by the aid of conduit 52 having compressor 53, by means of which the gases from receiver 50 may be forced into pipe 18 leading to the heater 20. Reflux condensate from the fractionator 47 may be wholly or partly diverted from the process through pipes 54 and 55, but preferably this condensate is recycled through the system, a portion or all of it being recycled to cracking heater 2 through conduit 56. If desired a portion or all or this reflux condensate may instead be combined with the gases passing through polymerizing heater 20, by diverting the condensate through the conduit 57, the desired control being effected by aid of valves 58 and 59. Distillate collecting in receiver 50, which falls within the boiling range of the final desired product, may be withdrawn from the process through line 60, but is preferably instead passed through line 61 and blended with distillate from receivers 15 and 36, or alternatively, distillate from any two of receivers 50, 15 and 36, may be blended to produce a desired product.

If desired the heater or furnace 40 may be so operated as to convert the gases passing therethrough into mainly unsaturated gases, such as olefins or the like, which are well adapted for polymerization in the polymerizing heater 20, to which they may be conducted while hot, or after any desired degree of quenching, through line 85 having control valve 86, and line 82, having compressor 53. Suitable unsaturated gases from an external source may be introduced to the heater 20, through line 54' for treatment with gases from separator 16, if desired, either with or without other added gases or liquids from the additional sources mentioned.

As shown on the drawing the distillates from receivers 15 and 36 are subjected to stabilization to remove undesirably light gases therefrom. Distillate is withdrawn from receiver 15 through line 62, heated, for example by indirect heat exchange with hot products, e. g. tar or other hot products of the process, in heat exchanger 63, and introduced into stabilizer tower 64, wherein stabilization is accomplished in the usual manner, the undesirably light gases passing off from the top of the stabilizer through line 65 and into line 18 leading to polymerizing heater 20 or being diverted wholly or in part from the process through line 66. Reference numerals 67 and 67' indicate a pipe for introducing cooling liquid in the usual manner and a reboiler, respectively, to control the operation of the stabilizer. Stabilized distillate passes off from the bottom of the stabilizer through conduit 68, and may be separately withdrawn from the process through pipe 69, or instead passed through pipe 70 into line 61 which leads to receiving drum 71, blending with the other distillates being accomplished in this manner. Distillate from receiver 36 undergoes similar treatment in stabilizer 72, being passed thereto through line 73. The undesirably light gases pass off from the top of the stabilizer through line 74 into conduit 38 leading to heater 40, or part or all of these gases may be diverted from the process through pipe 75. Reference numeral 76 indicates a conventional refluxing line for controlling operation of the stabilizer. The stabilized distillate is withdrawn from the stabilizer tower 75 through pipe 77 and either separately withdrawn

through pipe 78, or passed into line 61 through connection 79, for blending in receiver 71 with distillate from one or more of the other receivers. The stabilizers 64 and 72 are preferably operated under substantially the same pressure as that of the fractionators 9 and 28, e. g. about 200 pounds per square inch, but if desired the pressure used in the stabilizers may be increased by aid of pumps 80 and 81 in the two lines 62 and 73 respectively. Where it is not desired to use stabilizers the pressures on the distillates in the receivers 15 and 36 may be reduced, either by operating the fractionators 9 and 28 at a lower pressure or by reducing the pressure by aid of control valves 82 and 83 respectively, thereby causing more of the undesirably light vapors or gases to be removed from the distillate in the receivers 15 and 36, leaving distillates having the desired freedom from light products. When it is not desired to use the stabilizers the distillates may be withdrawn from the process either for individual use, or for blending, through lines 84 and 85.

In operation it is preferable to segregate in the receiver 15 of the cracking heater a light naphtha distillate of relatively low end point with respect to the final desired product. In the case where ordinary motor fuel is being formed in the system the distillate in receiver 15 may have, for example, an end point of 250° to 300° F. This distillate will have a high anti-knock rating, having been produced by vapor phase cracking. It need not necessarily be sharply fractionated. The heavier products necessary to produce the final desired blend may then be segregated in either receiver 36 or receiver 50 or both, being formed by polymerization and/or pyrolysis of the gases resulting from the cracking operation and having a relatively high anti-knock rating. These distillates or one of them is preferably so formed as to supply the heavy naphtha fractions deficient in the distillate collected in receiver 15, the distillates then being blended to produce the final desired product. The fractionator 28 is preferably operated at substantially the same pressure as that of fractionator 9, e. g. 200 pounds per square inch, and may be operated at either higher or lower pressures as may be desired to produce the desired distillate.

The specific values that I have mentioned hereinbefore are merely illustrative of a specific set of conditions adapted for the carrying out of my invention, but other values may be used and may be found more advantageous in the case of different charging stocks and different desired final products. The specific conditions used may be varied considerably from the value set forth while still obtaining the benefits of the invention, the fundamental thought being that cracking is carried out under drastic conditions to produce high anti-knock gasoline fractions, comprising mainly the lower boiling constituents of gasoline, with the attendant formation of relatively large quantities of incondensable gases, and that these gases are subsequently treated to form high anti-knock products in the gasoline boiling range, it being preferable that the final product be produced by blending the distillate of cracking with that resulting from the conversion of the gases to liquids, the latter supplying the necessary heavy constituents. Various processes are known for converting gases to liquids in the gasoline boiling range, and those which I have specifically described hereinbefore are believed to be preferable, but other processes may be used instead. It should be noted that in the specific

arrangement which I have described in detail the gases are treated in two successive conversion steps, the result being that the mainly olefinic gases are first converted to liquids, and subsequently the mainly paraffinic gases are converted to liquids. Instead of following this procedure the gases could first be separated into olefinic and paraffinic constituents by selective solvent action of naphtha, triethanolamine or similar solvent or in any other manner and each separate constituent subsequently subjected to the conversion process best adapted to form therefrom the largest amount of liquid products falling in the desired boiling range. The process is also applicable where the initial cracking operation is carried out at high cracking per pass under relatively high pressure, e. g. 1000 pounds per square inch and upwards, and relatively high temperatures, with short times of contact.

20 While I have described a particular embodiment of my invention for the purpose of illustration, it should be understood that various modifications and adaptations thereof, occurring to one skilled in the art, may be made within 25 the spirit of the invention as set forth in the appended claims.

I claim:

1. The process of treating relatively heavy hydrocarbon oil for the production of gasoline 30 which comprises subjecting said hydrocarbon oil to a cracking operation to cause formation of relatively high anti-knock gasoline fractions, separating from the resulting cracked products distillate falling in the desired boiling range but 35 having an end point of from 250° to 300° F., that is to say, an end point lower than that desired for the final product, a condensate containing constituents boiling above 300° F. and within the upper portion of the boiling range of the desired 40 product, heavier products and gas, returning at least a part of said condensate to the cracking operation for further treatment, subjecting said gas to heat and pressure to effect conversion of constituents thereof to liquid in the desired boiling 45 range and heavier normally liquid hydrocarbons, recycling heavier normally liquid hydrocarbons thus obtained to the cracking operation to effect drastic cracking thereof and blending liquid so formed with said gasoline fractions first 50 mentioned to form a final product having the desired boiling point range.

2. A process in accordance with claim 1 wherein unconverted gases resulting from heat and pressure conversion of the gases are subjected to 55 high-temperature low-pressure conversion conditions for the production of additional liquid in the desired boiling range.

3. A process in accordance with claim 1 wherein unconverted gases resulting from heat and pressure conversion of the gases are subjected to elevated temperature to effect conversion of constituents thereof to liquid, fractionating the products of conversion to separate liquid in the desired boiling range of the final product from 60 heavier liquid and combining heavier liquid thus obtained with gases from the cracking operation prior to the subjection thereof to heat and pressure.

4. The process of producing gasoline from relatively high-boiling oil which comprises cracking said oil under high temperature and low pressure to produce a high yield of low-boiling products, fractionating the cracked vapors thereby produced to separate a cracked gasoline distillate 75 deficient in constituents boiling above 250° F., a

higher-boiling condensate including constituents boiling immediately above 300° F. and a lower-boiling fraction containing a relatively high percentage of normally gaseous unsaturated constituents, subjecting said higher-boiling condensate to further cracking to produce lower-boiling products, the cracked vapors thereby produced being commingled with those produced by the cracking of the high-boiling oil comprising the original charging stock for fractionation, subjecting at least a portion of said lower-boiling fraction to elevated pressure and temperature for a sufficient period of time to effect polymerization of constituents thereof to a normally liquid gasoline-like product lying within a gasoline boiling-point range and heavier normally liquid hydrocarbons, recycling heavier normally liquid hydrocarbons thus obtained to the relatively high-boiling oil undergoing cracking to effect cracking thereof, and blending said product with said 20 cracked gasoline distillate to form a balanced gasoline product of high anti-knock value.

5. The process of treating relatively heavy hydrocarbon oil for the production of gasoline, which comprises subjecting said relatively heavy oil to a high temperature cracking operation to cause drastic cracking thereof, separating the resulting cracked products into vapors and a liquid residue, forming from said vapors a distillate falling in the boiling range of the final desired products but having an end point of from 250° to 300° F., that is to say, an end point lower than that desired for the final product, and a condensate containing constituents boiling above 300° F. and within the upper portion of the boiling range of the desired product, and heavier, returning at least a part of said condensate to the cracking operation for further treatment, removing incondensable gases from the products of conversion, subjecting gases thus obtained to elevated temperature and pressure to effect polymerization of constituents thereof to a liquid distillate falling in the boiling range of the final desired product and having an end point corresponding to that of the final desired product and heavier normally liquid hydrocarbons, recycling heavier normally liquid hydrocarbons thus obtained to the cracking operation to effect drastic cracking thereof, and blending the first and second mentioned distillates to form the final desired 50 product.

6. A process in accordance with claim 5 wherein said liquid distillate second-mentioned consists predominantly of the heavier gasoline fractions necessary to supply the deficiency there- 55 of in the distillate first-mentioned.

7. The process of treating relatively heavy hydrocarbon oil for the production of gasoline which comprises subjecting said hydrocarbon oil to a cracking operation to cause formation of relatively high anti-knock gasoline fractions, separating from the resulting cracked products distillate falling in the desired boiling range but having an end point of from 250° to 300° F., that is to say, an end point lower than that desired for the final product, a condensate containing constituents boiling above 300° F. and within the upper portion of the boiling range of the desired product, heavier products and gas, returning at least a part of said condensate to the cracking operation for further treatment, subjecting said gas to heat and pressure to effect conversion of constituents thereof to normally liquid hydrocarbons, separating the products of conversion into a liquid hydrocarbon in the de- 75

sired boiling range, heavier hydrocarbons and unconverted gases, blending liquid hydrocarbons so formed with said gasoline fractions first-mentioned to form a final product having the desired boiling range, subjecting unconverted gases to elevated temperature to effect conversion of constituents thereof to liquid, fractionating the prod-

ucts of conversion to separate liquid in the desired boiling range of the final product from heavier liquid and combining heavier liquid thus obtained with gases from the cracking operation prior to the subjection thereof to heat and pressure. 5

HAROLD V. ATWELL.
